UNITED STATES PATENT OFFICE.

MILTON C. HALL, OF BAKERSFIELD, CALIFORNIA.

DESIGN FOR A CALENDAR.

SPECIFICATION forming part of Design No. 33,572, dated November 20, 1900.

Application filed September 17, 1900. Serial No. 30,386. Term of patent 14 years.

To all whom it may concern:

Be it known that I, MILTON C. HALL, a citizen of the United States, residing at Bakersfield, county of Kern, State of California, have 5 invented and produced a new and original Design for Calendars, of which the following is a specification, reference being had to the accompanying drawing, forming part thereof.

The figure is an elevation showing my design.

As shown in the drawing, the leading or material feature of my design consists of the representation of a watch A, with the stem and ring 2, and arranged within the inner 15 periphery of A are a series of small representations of dials 4, having figures indicative of the hours and the names of cities in different longitudes around the world, with the hands on the dials pointing to the hours, indicating 20 the time in those cities with relation to each other. Interior to these small dials and concentric with the outer rim of A is a pictorial representation of a globe, showing a part of the world, as at 5.

The main dial A is supported upon a rectangular base subdivided for the number of days contained in a month, as shown at 6. The ends of this base are connected with supporting-posts 7, one of which has upon the top the figure of Time, with scythe and hour-glass, as at 8, and upon the other the figure of the Goddess of Liberty, as at 9.

The bases of the posts 7 are represented as spanning the Golden Gate, resting in the waters thereof, and upon each side are views of 35 the elevations of land and connected features between which the waters of the strait flow.

Having thus described my invention, what I claim as new, and desire to secure by Letters Patent, is—

The design for a calendar as herein shown and described.

In witness whereof I have hereunto set my hand.

MILTON C. HALL.
